CLAIM

(72) Inventor: **Barbara Ann Schindel (Heinlein)**,
Fond du Lac, WI (US)

The ornamental design for a two side cutting board with support base, as shown and described.

(**) Term: **15 Years**

(21) Appl. No.: **29/620,113**

DESCRIPTION

(22) Filed: **Jul. 7, 2016**

FIG. 1 is a front perspective view of a two side cutting board resting in the support base with hand grips facing upward, showing my new design;

(51) LOC (11) Cl. **07-04**

FIG. 2 is a front perspective view, with the hand grips resting in the support base thereof;

(52) U.S. Cl.

FIG. 3 is a front perspective view with the hand grips facing to the right side, (hand grips facing to the left is a mirror image) resting in the support base thereof;

USPC **D7/698**

FIG. 4 is a front perspective view laying flat on a flat surface thereof;

(58) **Field of Classification Search**

FIG. 5 is a perspective view of the back cutting side thereof;

USPC D7/543, 549, 550.1, 586, 698–699;
D32/55–57

FIG. 6 is a perspective view of the back cutting side facing forward resting in the support base thereof;

CPC A47J 47/00; A47J 47/005; A47J 47/20;
B26D 7/0006; B26D 7/018; B26D 7/20;
B23D 21/00; B23K 37/04; B23K 37/053;
B23Q 16/001

FIG. 7 is a perspective view of the top slot, of the support base, facing forward thereof.

See application file for complete search history.
